(57) **CLAIM**

I claim the ornamental design for the chair, as shown and described.

DESCRIPTION

FIG. 1 is a front elevational view of a chair embodying my new design;

FIG. 2 is a left-side elevational view thereof;

FIG. 3 is a right-side elevational view thereof;

FIG. 4 is a top plan view thereof;

FIG. 5 is a rear elevational view thereof;

FIG. 6 is a front elevational detail of the upper center of the chair back, illustrating the ornamentation thereon in enlarged detail; and,

FIG. 7 is a right side elevational detail of the chair arm handrest and seat, illustrating the ornamentation thereon in enlarged detail.

1 Claim, 7 Drawing Sheets
